UNITED STATES PATENT OFFICE

164,691

BLOUSE

Jolly Kaye, New York, N. Y.

Application September 20, 1949, Serial No. 5,099

Term of patent 3½ years

(Cl. D3—25)

To all whom it may concern:

Be it known that I, Jolly Kaye, a citizen of Hungary, residing at New York city, in the county of New York and State of New York, have invented a new, original, and ornamental Design for a blouse, of which the following is a specification, reference being had to the accompanying drawing, forming part thereof.

In the drawing:

Fig. 1 is a front view of a blouse, showing my new design;

Fig. 2 is a rear view thereof.

I claim:

The ornamental design for a blouse, substantially as shown.

JOLLY KAYE.
